CLAIM

The ornamental design for a tire sidewall, as shown and described.

DESCRIPTION

FIG. 1 is a side elevational view of a first, second, and third embodiment of our new tire sidewall design;

FIG. 2 is a cross-sectional view along cross-section line 2-2 of FIG. 1 of a first embodiment of our new tire design;

FIG. 3 is a cross-sectional view along cross-section line 2-2 of FIG. 1 a second embodiment of our new tire design; and,

FIG. 4 is a cross-sectional view along cross-section line 2-2 of FIG. 1 of a third embodiment of our new tire design.

In the drawings, the broken lines represent environmental subject matter that forms no part of the claimed design.
